UNITED STATES PATENT OFFICE.

JOHN KNOX MORRIS, OF NEWHALL, CALIFORNIA.

HOLDING DEVICE FOR NEWSPAPERS.

No. 904,979.

Specification of Letters Patent.

Patented Nov. 24, 1908.

Application filed May 8, 1908. Serial No. 431,702.

To all whom it may concern:

Be it known that I, JOHN KNOX MORRIS, a citizen of the United States of America, residing at Newhall, in the county of Los Angeles and State of California, have invented new and useful Improvements in Holding Devices for Newspapers, of which the following is a specification.

This invention relates to holding devices for newspapers and packages, and one of the principal objects of the same is to provide a device of comparatively simple construction which will securely hold a newspaper or other package delivered to a residence and to hold the same against surreptitious withdrawal by unauthorized persons.

Another object of the invention is to provide a device of the character referred to which shall be ornamental, or at least not unsightly, and which will be provided with means whereby the household will be notified when a newspaper or package has been deposited in the holder.

Still another object of the invention is to provide a holder made in the form of an animal or bird in which the jaws of the animal or bird will close upon a newspaper or other package and hold it firmly until it is released by the person opening the door to obtain the same.

These and other objects may be attained by means of the construction illustrated in the accompanying drawing, in which,—

Figure 1 is a front elevation of a holding device made in accordance with my invention shown attached to a door casing and showing a portion of a door hinged to the casing. Fig. 2 is a central vertical section of the same. Fig. 3 is a sectional view on the line 3—3 of Fig. 2. Fig. 4 is a detail view showing the device for releasing the jaws of the holder.

Referring to the drawing for a more specific description of my invention, the numeral 1 designates the door, and 2 is the door frame, said door adapted to be hinged in the usual manner to said frame. Secured in the panel of the door frame is my holder for newspapers and packages consisting of a base plate 3 provided with suitable screw holes 4 for the screws 5 which secure the device in place. As shown in the drawing, the base plate has formed integral with it a lion's head 6. It will be understood, however, that the head of another animal or other bird, or, in fact, if need be,

a plain casing of the required dimensions may serve my purpose. In the front part of the head is a mouth 7 forming an opening of sufficient size to admit a newspaper or other parcel of similar character.

Pivoted upon the transverse rods 8 within the head or casing is a pair of jaw members 9, each provided with inwardly disposed teeth 10 projecting beyond the lips of the mouth 7. The base portion 3 is provided with a recess 11, and the door casing is also recessed at 12 in line with the recess in the base plate. The jaw members 9 extend through these recesses and are pivoted to the rods 8, as clearly illustrated in Figs. 2 and 3 of the drawings.

Conductor wires *a*, *b* are connected to the binding posts *c* secured into the members 9, said conductor *a* leading to a battery *d*, and from thence to a bell *e*, while the conductor *b* leads from the binding *c* to said bell.

A sleeve 14 secured to an integral bracket 15 within the head or casing has a ring or gasket of insulated material therein, and extending through said gasket is a rod 17 having upon its front end a curved yoke 18 and upon its rear end a wedge shaped head 21. Surrounding the rod 17 is a spiral spring 19, one end of which bears against the yoke 18 and the opposite end against a collar 20 positioned adjacent the gasket 16. This spring 19 is adapted to normally force the yoke 18 forward towards the mouth 7. Journaled on the sides of the members 9 are rollers 22, against which the head 21 of the rod 17 is forced to close the teeth 10 when papers are deposited in the mouth 7 and pushed sufficiently to compress the spring 19 and force the teeth into engagement with the papers.

Connected to the shaft 17 is a bar 23 which extends laterally through the side of the casing 6 and is provided upon its outer end with a short rack bar 24. A pawl 25 connected to a spring arm 26 engages the teeth of the rack bar 24 when the door 1 is closed, and secured to the door is a plate 27 which carries the spring arm 26 and the pawl 25.

The operation of my invention may be briefly described as follows: The newspaper or other package is deposited in the mouth 7 between the teeth 10 and pushed back sufficiently to push the yoke 18 and to move the wedge-shaped head between the rollers 22, thus completing a circuit through the con-

ductors *a*, *b* to the bell *c* and ringing said bell continuously until some person comes to the door and opens the same. It will be understood that the door 1 opens inwardly, 5 and that as the pawl 25 is withdrawn from the rack bar on opening the door, the wedge-shaped head 21 is released from between the rollers 22, thus breaking the circuit and leaving the jaws in the condition shown in 10 Fig. 2 ready for another paper or package.

From the foregoing it will be obvious that my invention is of comparatively simple construction, can be used without the electrical annunciator and is strong, durable 15 and efficient in use.

Having thus described the invention, what is claimed as new, is:—

1. A holder for newspapers and packages comprising a casing having an opening 20 therein, a pair of jaw members pivoted within the casing and extending beyond the

opening in said casing, a rod mounted to slide in the sleeve within the casing and provided with a yoke and spring, and means whereby an electrical connection is established when the yoke is pushed inward. 25

2. In a device of the character described, a casing having an opening in the front portion thereof, a pair of jaw members, a rod having a yoke on the end thereof, a wedge-shaped head on the opposite end thereof, a spring surrounding said rod for forcing the same outwardly, and electrical means for ringing a bell when said rod is forced backwardly by a paper or parcel. 30 35

In testimony whereof I affix my signature in presence of two witnesses.

JOHN KNOX MORRIS.
